DRIVE-IN BOLT

Kazuo Murakoshi, Tokyo, Japan, assignor to Kabushiki
Kaisha Murakoshi Seira Seisakusho, Tokyo, Japan

Filed July 24, 1973, Ser. No. 382,072

Claims priority, application Japan Feb. 12, 1973

Term of patent 14 years

Int. Cl. D8—08

U.S. Cl. D8—272

FIG. 2

FIG. 3

FIG. 1

FIG. 4

FIG. 6

FIG. 5

FIG. 7

FIG. 1 is a front elevation of a drive-in bolt showing my new design;

FIG. 2 is a top plan view thereof;

FIG. 3 is a left side elevation thereof;

FIG. 4 is a right side elevation thereof;

FIG. 5 is a bottom plan view thereof;

FIG. 6 is a rear elevation thereof; and

FIG. 7 is a perspective view thereof.

I claim:

The ornamental design for a drive-in bolt, as shown and described.
